MULTIPLE OUTLET CONNECTOR

Glen Harpster, Los Angeles, Calif.

Application October 10, 1949, Serial No. 120,469

4 Claims. (Cl. 339—159)

1

This invention relates generally to improvements in multiple outlet electrical connectors and is a continuation in part of my co-pending application, Serial No. 646,995, filed February 12, 1946, now Patent No. 2,500,987, issued March 21, 1950.

Prior connectors have been subject to several disadvantages which are sought to be overcome by the invention disclosed in my co-pending application and by the present device. In order to be made available on the market at the low price the public demands, every effort must be made to adapt the design of electrical connectors to mass production manufacturing and assembly methods. In my prior application, Serial No. 646,995, filed February 12, 1946, I disclosed a design marking an advance over the prior art in this regard, and my present invention discloses additional modifications.

Aside from the factors affecting cost of production, it is a frequent observation that when one wishes to disengage an electrical plug from the connector on the end of an extension cord, he pulls or jerks the connection in such a way as to impose on the electrical connections within the connector a physical strain. Conductors become loosened from the strain, and eventual failure of the connector is not uncommon. The above difficulty is increased if the electrical distributor within the connector is permitted any substantial movement, since continual flexing of the strands of the conductors contributes to breaking the strands.

My invention provides means for gripping the insulation of an extension cord leading to a connector in such a way that pulling or jerking the extension cord will not result in any strain being placed upon the electrical connections between the conductors and the interior electrical distributors. Likewise, my present invention provides means for preventing movement of the distributor within the connector which would flex or strain the wire strands of the conductor.

It is therefore an object of this invention to provide an electrical connector which when used on the end of an extension cord grips said cord by means separate from the electrical connection between the cord and the connector.

Another object of this invention is to disclose an electrical connector which when inserted into a female socket will be retained therein in such a way as to minimize the possibility of accidental dislodgement.

A further object is to disclose a connector

having means for minimizing movement of the internal electrical distributors with respect to the conductors soldered or otherwise attached thereto.

5 Another object of my invention, in one of its embodiments, is to disclose an improved design of electrical connector using only two identical dielectric body members and two identical electrical distributors, thus facilitating manufacture and assembly operations.

10 A further object is to disclose a multiple outlet electrical connector having electrical distributors affording low contact resistance to a male prong.

15 A still further object is to provide such a connector whose design minimizes the danger of arc-overs or short circuits within the connector.

20 Other objects and purposes will become apparent from a study of the following description taken in connection with the accompanying drawings, in which:

Fig. 1 is a perspective view of an embodiment of my invention in the form of a multiple outlet having a pair of male prongs adapted to be inserted into a female socket.

25 Fig. 2 is a perspective view of another embodiment of my invention adapted to be connected on the end of a conventional extension cord.

30 Fig. 3 is a view of an electrical distributor as used in the first embodiment of my invention, with a male prong attached thereto.

35 Fig. 4 is a view of the electrical distributor as used in the second embodiment of my invention, including a sectional, fragmentary view of the body members showing the means for minimizing relative movement of the distributor and electrical conductor attached thereto.

40 Fig. 5 is a sectional view taken on line V—V of Fig. 1.

Fig. 6 is a sectional view taken on line VI—VI of Fig. 2.

45 Fig. 7 is a sectional view taken on line VII—VII of Fig. 5, with the upper body member shown spaced slightly apart from the lower body member.

50 Fig. 8 is an enlarged fragmentary view taken on line VIII—VIII of Fig. 6, with the upper body member shown in assembled position.

Fig. 9 is a perspective view of another embodiment of my invention.

Fig. 10 is a view taken on line X—X of Fig. 9.

Fig. 11 is a sectional view taken on line XI—XI of Fig. 10.

3

Referring to the drawings, Fig. 1 shows a connector 14 including two identical body members 15 and 16 held together by connecting or clamping means such as a small bolt 17 and a nut 18, said bolt 17 passing centrally through a counter-bored passage in the two body members 15 and 16. It will be understood that other connecting means may be used to retain body members 15 and 16 in assembled relation. For instance, I may provide a rod or strip, preferably metallic, adapted to frictionally or otherwise grip the internal surfaces of the central passageway through body members 15 and 16; or a tubular member upset at each end may be used as illustrated at 82 in Figs. 9, 10 and 11. Body members 15 and 16 are positioned together so as to form two parallel end surfaces 19 and 21. Lying in planes perpendicular to end surfaces 19 and 21 are a plurality of sides 22, and in the embodiment shown in Fig. 1, each side 22 is provided with a pair of prong-receiving apertures 23 and 24. All apertures lie in a pair of spaced parallel planes, apertures 23 defining one of said planes and apertures 24 defining the other plane.

Within the connector body 14 and communicating with apertures 23 and 24 is a pair of housing recesses 25 and 26, said recesses being divided by a division member or web partition 27 formed integrally with body members 15 and 16 and extending across the interior of body 14. Web partition 27 lies in a plane parallel to end surfaces 19 and 21. I preferably include an enlarged central boss 28 in web 27, and formed centrally in boss 28 is hole 29 through which screw 17 extends.

In each housing recess 25 and 26 is disposed an electrical distributor 31 of a resilient metal having a high current-carrying capacity. I preferably form distributor 31 in the form of a disk having a slightly convex shape as most clearly appears in Figs. 5 and 6, the convex surface of the distributor facing inwardly. Distributor 31 includes a plurality of inwardly extending fingers 32 slightly inclined to the plane of recess 25 or 26, and has an integral projecting lug 33 having opposed shoulders. Formed in distributor 31 on the radius bisecting lug 33 may be one or more holes 34 for attaching electrical conductors thereto.

Particularly with reference to the embodiment shown in Figs. 1, 3 and 5, an electrical male prong 36 may be attached to distributor 31 in the region of lug 33 and holes 34 by rivets or other means 37. Slight divergence of prongs 36, when obtained, minimizes accidental dislodging of the connector from a female socket or wall outlet. Each resilient finger of the distributor is at a slight inclination to the walls of the recess in which it is held, thereby insuring thorough contact with an entering male prong.

As shown most clearly in Fig. 7, body members 15 and 16 are provided with cooperating locating means including hemispherical projections 41 and cooperating hemispherical recesses 42. When body members 15 and 16 are placed together to form body 14, projections 41 are received into recesses 42, such junction serving to align the two body members 15 and 16 with respect to each other.

Another embodiment of my invention is shown in Fig. 2 wherein one side of body member 15 and the corresponding side of body member 16 are notched so that centrally on one of sides 22 of body 14 there is provided a port 46 adapted to permit the entrance of conventional two-con-

4

ductor electrical cord 47. The conductors of cord 47 are fastened to holes 34 in distributors 31 by soldering, rivets or other means at 48 and 49.

In order to prevent flexing and eventual parting of the conductors of electrical cord 47 at their points of attachment 48 and 49 with electrical distributors 31, it is desirable to prevent the rotation of distributors 31 within their housing recesses 25 and 26. As most clearly seen in Fig. 4, I provide in body members 15 and 16 adjacent port 46 a pair of recesses having substantially flat surfaces 55 and 56. Recesses 55 and 56 are located on each side of port 46 and, when body 14 is assembled, serve to receive the shoulders of projecting lug 33 of distributor 31. Distributors 31 are thus restrained from rotation within their housing recesses 25 and 26, but are permitted a limited amount of axial movement within said recesses in order to insure electrical contact between inwardly projecting fingers 32 and prongs of a conventional male plug entering apertures 23 and 24. It will be noted that the distributors 31 are of identical contour whether used in the outlet plug or the cord conductor.

With particular reference to Fig. 8, it can there be seen how cord 47 is gripped by body members 15 and 16. Disposed in the upper and lower surfaces of port 46 are raised clamping teeth 51 and 52, which are formed integrally with body members 15 and 16 respectively and when said body members are placed together forming body 14, the distance separating the teeth 51 of body member 15 from the teeth 52 of body member 16 is appreciably less than the thickness of electric cord 47. The yielding insulation of cord 47 is therefore pinched by teeth 51 and 52, and it can be seen that force exerted on cord 47 in the form of jerks and tugs will not be transmitted to electrical connections 48 and 49. Hence those connections are not subjected to the strain which would otherwise cause eventual failure. Teeth 51 and 52 may be formed with their longitudinal dimensions perpendicular to cord 47, or as shown, slightly inclined to said perpendicular. Since the body portions are identical, the opposing and inclined teeth will assume a spaced and crossed relation, shown in Fig. 8, when in use.

The embodiment of my invention adapted to be attached permanently on the end of an extension cord, as illustrated in Figs. 2, 4, 6 and 8, is provided with aligning means including projections 41 and recesses 42, similar to those already described in connection with Figs. 5 and 7. I may provide aligning means 41 and 42 adjacent teeth 51 and 52, although I have found that this is not usually necessary since the presence of cord 47 in port 46 prevents relative movement of body members 15 and 16.

Although the integral web 27 preferably extends across and lends strength to the entire body portion, and connects the sides and central boss 28 (as in Fig. 5), it may be reduced or even eliminated on one or both sides of division member or boss 28. For example, as shown in Fig. 6, web 27 is entirely eliminated in the right half of body portion 16 in order to accommodate the conductors of cord 47 passing to their points of attachment 48 and 49 with distributors 31. When web 27 is reduced or eliminated on both sides, division member or central boss 28 is the only portion of dielectric body member 16 extending centrally of the connector from one body member to the other.

A third embodiment of my invention appears

in Figs. 9, 10 and 11. Body members 61 and 62 are identically formed and when assembled, as shown in Figs. 9 and 11, include between them a prong-spacing core 63. Body members 61 and 62 and core 63 are made of dielectric material and prong-spacing core 63 includes an integral, centrally disposed web partition or division member 75 dividing the interior of the assembled connector into two identical spaced recesses 80 and 81.

Body members 61 and 62 are provided with substantially flat parallel end surfaces 64 and 65, and have a plurality of angularly related sides 66, each of said sides including a pair of prong-receiving apertures 67 and 68, said apertures lying in planes parallel to the end surfaces. Each aperture communicates with one of the two spaced recesses 80 and 81 which also lie in planes parallel to the end surfaces.

One of the sides 66 may be provided with a pair of electrical conducting prongs 69 constituting a male connection for insertion into the conventional female wall outlet or other socket. Prongs 69 are attached at their inner ends to electrical distributors 70 and 71 held in the spaced recesses 80 and 81. The entire structure is held in assembled relation by connecting or clamping means 82 passing through the center of body members 61 and 62 and prong-spacing core 63. Connecting or clamping means 82 may be a tubular metal element upset at each end as shown, or may take other forms well known in the art. As seen in Fig. 10, each of the plurality of inwardly projecting fingers 72 of distributor 71 may have formed therein a dimpled protuberance 73 adapted to engage a hole formed near the end of conventional male prong, thereby assisting in retaining such prong in contact with finger 72.

In order to prevent relative movement of body members 61 and 62 and prong-spacing core 63, I may provide aligning means including hemispherical protuberances 76 in core 63 and hemispherical recesses 77 and 78 in body members 61 and 62.

Changes and modifications in the present invention will suggest themselves to those skilled in the art. For instance, any number of sides of the connector body may be used with a corresponding number of inwardly projecting fingers in the electrical distributors. All such changes are intended to be embraced within the scope of the appended claims.

I claim:

1. A multiple outlet electrical plug comprising: a body of dielectric material, said body having a pair of parallel end surfaces and a plurality of angularly related substantially flat sides in planes perpendicular to said end surfaces; a pair of spaced recesses in the body, said recesses lying in planes parallel to the end surfaces and perpendicular to the planes of said sides, each of said recesses including opposing wall faces of dielectric body material; a pair of identical, slightly convex, disk-shaped unitary electrical distributors of resilient metal in said recesses, each distributor having a continuous peripheral portion and a plurality of integrally formed, resilient fingers extending inwardly therefrom, said fingers being slightly inclined to the plane of the recess, each said distributor having a surface area virtually equal to that of its housing recess and af-

forged a limited axial movement therein; and a pair of parallel prong-receiving apertures in each side of the body, each of said apertures being in communication with one of the recesses and arranged to guide a prong into sliding contact with one of said resilient fingers, all of said apertures lying in a pair of spaced, parallel planes, each of said last-named planes passing substantially through the middle of the recess in communication with the apertures in such plane.

2. In a multiple outlet connector, the provision of: a body of dielectric material having a plurality of intersecting planar side walls and a pair of spaced recesses therein perpendicular to said side walls, said side walls including a plurality of pairs of prong-receiving apertures communicating with the recesses, the apertures lying in spaced parallel planes perpendicular to the side walls; and a pair of identical, slightly convex, disk-shaped, unitary electrical distributors of resilient metal in said recesses, each distributor having a substantially continuous peripheral portion and a plurality of integrally formed, resilient fingers extending inwardly therefrom, said peripheral portions being slightly spaced from said planes and said fingers intersecting the planes.

3. A multiple outlet connector as stated in claim 2 wherein each of said fingers is tapered from a relatively broad base merging with its respective peripheral portion to a relatively narrow tip at its innermost end.

4. A multiple outlet connector comprising: a box-like body of dielectric material having a pair of parallel end surfaces and a plurality of angularly related, substantially flat side walls extending perpendicularly to and connecting the end surfaces, each of a plurality of said side walls having a pair of prong-receiving apertures formed therein, said pairs of apertures lying in a pair of spaced parallel planes; a pair of identical, slightly convex, disk-shaped electrical distributors of resilient metal within the body, each distributor having a peripheral portion disposed adjacent one of said planes and a plurality of integrally formed fingers slightly inclined to said plane and extending inwardly from said peripheral portion and intersecting said plane, each of said fingers being tapered from a relatively broad base merging with its respective peripheral portion to a relatively narrow tip at its innermost end.
